UNITED STATES PATENT OFFICE.

JOHN J. WEICHER, OF CHICAGO, ILLINOIS.

MACHINE FOR EXTRACTING FIBER FROM FIBROUS PLANTS.

SPECIFICATION forming part of Letters Patent No. 439,913, dated November 4, 1890.
Application filed May 24, 1890. Serial No. 353,027. (No model.)

To all whom it may concern:

Be it known that I, JOHN J. WEICHER, of Chicago, in the county of Cook and State of Illinois, have invented a new, useful, and Improved Machine for Extracting Fiber from Fibrous Plants, of which the following is a full, clear, and exact description, reference being had to the accompanying drawings, forming a part of this specification, in which—
10. Figure 1 is a side view, in longitudinal section, of my improved machine. Fig. 2 is a plan view of the same. Fig. 3 is a vertical sectional view taken upon the line $x-x$, Fig. 1, viewed in the direction of the arrow there shown. Fig. 4 is a plan view, in horizontal section, of the revoluble drum which acts upon the fiber; and Fig. 5 is a longitudinal sectional view in detail of the sprocket-chains and beveled cross-bars attached thereto.

20. Like letters of reference in the different figures indicate corresponding parts.

The object of my invention is to provide a simple, cheap, and durable machine whereby the fiber may be separated from the pulp of fibrous plants in an economical and satisfactory manner, all of which is hereinafter more particularly described, and definitely pointed out in the claims.

Referring to the drawings, a represents the 30 frame of my improved machine, upon which is mounted in suitable bearings b b' c a series of transverse shafts b^2 b^3 c' . Upon each of said shafts is mounted a pair of sprocket-wheels b^4 b^5 c^2 . Trained over the wheels b^4 b^5 35 are sprocket-chains d d , each link of the chain upon one side of the machine being connected with one or more, but preferably two, cross-bars e , (better shown in Fig. 5,) by means of rivets or otherwise, which bars are beveled or triangular in cross-section and arranged side by side, so that when viewed from the top, as in Fig. 2, they form a table having a series of transverse grooves therein. Set-screws f f are provided in the bearing of 45 the shaft b' for the purpose of adjusting the tension of the chains d . One or more idle rolls or drums g , Fig. 1, is or are mounted in suitable bearings upon the frame and arranged beneath the upper portion of the endless chains d to prevent the latter from sagging.

50. A secondary pair of endless chains h h are

trained over the wheels b^4 , outside of the chains d d , being made longer than the latter and carried around sprocket-wheels c^2 , mounted upon the shaft c' . A series of beveled cross-bars j are arranged to connect the chains h at intervals, substantially as shown, and being upon the inside of said chain-links, whereas the bars e are upon the outside of the chains d , said bars upon the respective 60 chains being adjusted to mesh or interlock with each other like the teeth of cog-wheels, as clearly indicated in Fig. 5, so that leaves interposed between the slats j e , as herein-after stated, are grasped thereby and firmly held during the passage of the bars j , by which they are clamped, from the wheels b^5 , around the wheels b^4 , and back beneath said wheels b^5 . A pulley k , Fig. 2, connected with a source of power, serves to actuate the shaft 70 b^2 , together with said sprocket-chains.

At the front of the machine is a casing l , preferably made of sheet metal, in which is located a hollow revoluble drum m , mounted upon a hollow shaft m' , connected by means 75 of a pipe-hose n or otherwise with a source of water-supply, while a pulley o , rigidly connected by means of a shaft o' to the drum, serves to revolve the latter. The shaft m' is provided with openings m^2 therein for the admission of water to the drum m , which is also provided with a series of perforations m^3 in its periphery. A series of blunt knives or metallic scrapers p is rigidly secured to the periphery of the drum m and arranged to 85 pass during the rotation of the drum in close proximity to an opening q , formed in the rear of the case l for the admission of the plant leaves to said case. Upon the bottom of said opening is provided a rounded lip q' . The 90 shell l is rounded beneath to conform to the shape of the drum m , and a spout l' is formed therein, which serves to carry off the pulp. A drum r , Figs. 1 and 2, mounted loosely upon arms r' , pivoted to brackets r^2 , serves 95 to direct the plant leaves toward the opening q and insure their entrance lengthwise therein, and serves also to mash the plants.

Having thus described the construction of my improved machine, I will now describe its 100 operation. The shaft b^2 is rotated at a moderate rate of speed, while the drum m is be-

ing revolved with high velocity, water being continuously forced therein, as indicated. The plant leaves *s* to be treated are laid upon the platform formed by the slats *e* immediately above the shaft *b* and at a time when one set of bars *j* are about to engage with the bars *e*, as clearly shown in Figs. 1 and 2. The leaves *s* are firmly grasped between the two sets of bars and conveyed in the direction of the arrow, Fig. 1, beneath the drum *r* and into the opening *q*, where they are acted upon and abraded by the scrapers of the revolving drum and thoroughly washed with the water therefrom, the pulp being carried off with the water through the spout *l*. The fiber of the plant, being still clamped between the bars, as stated, is then withdrawn from the opening *q* and carried on until it passes beneath the shaft *b*, where the bars *j* are disengaged from contact with the bars *e*, and the fiber being thereby released falls to the ground.

Having thus described my invention, I claim:

- 25 1. In a fiber-extracting machine, the combination, with a revoluble drum provided with a series of scrapers thereon, of two sets of endless sprocket-chains, one longer than the other, mounted upon sprocket-wheels in operative proximity to said drum, the longer set of chains being trained over the shorter, which latter have cross-slats attached thereto throughout their length, while the other is provided with similar slats arranged in sets 30 at intervals from each other, whereby the slats upon the outermost chains may engage with those upon the others and firmly clamp between them fibrous plants placed therein, pass them into conjunction with the scrapers, 35 and release them at a given point, substantially as shown and described.
- 40 2. In a fiber-extracting machine, the combination, with two sets of chains mounted and having slats arranged thereon, as described, of 45 a hollow revoluble drum having scrapers upon its periphery in operative proximity to said

slats, perforations in the shell of said drum, means for forcing water within the drum and through said perforations, and means for actuating said chains and drum, substantially as shown and described. 50

3. In a fiber-extracting machine, two sets of endless chains, one longer and trained over the other and both mounted upon wheels, counter-part intersecting slats attached to said chains, 55 respectively, those upon the outermost chains being arranged at intervals from each other, in combination with a revoluble drum having scrapers upon its periphery, a case for enclosing said drum, and an opening in said case opposite the upper level of said chains, whereby the plants grasped by said slats may be introduced in said opening and the fiber withdrawn after having the pulp separated therefrom by the scrapers, substantially as 60 shown and described.

4. The combination, with the chains *d* *h*, mounted as described, of slats *e* *j*, means for actuating said chains, a revoluble drum having scrapers upon its periphery in operative 70 proximity to said chains, and means for actuating said drum and for forcing water upon the fibrous plants while being acted upon by said scrapers, substantially as shown and described. 75

5. In a fiber-extracting machine, the combination of the chains *d* *h*, mounted as described, one having slats *e* secured upon the outside thereof throughout its length and the other having slats *j* attached to the inside and 80 arranged at intervals thereon, whereby said two sets of slats may engage with and mesh into each other, substantially as shown and described.

In testimony whereof I have signed this 85 specification, in the presence of two subscribing witnesses, this 14th day of May, 1890.

JOHN J. WEICHER.
